Wesley G. Carr
ATTORNEY

UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

DEAD-END TERMINAL.

Application filed April 7, 1920. Serial No. 371,959.

To all whom it may concern:

Be it known that I, JAMES M. BROWN, a citizen of the United States, and a resident of Pittsburgh, in the county of Allegheny and State of Pennsylvania, have invented a new and useful Improvement in Dead-End Terminals, of which the following is a specification.

My invention relates to electrical dead-end terminals or connectors and particularly to 10 adjustable terminals for dead ending and adjusting the slack in conductors.

One object of my invention is to provide a device of the above indicated character that 15 shall be simple and durable in construction, economical to manufacture and effective in operation.

Another object of my invention is to provide an electrical terminal, constructed on 20 the order of a turnbuckle, to permit the adjustment of a conductor, in which a main body portion of insulating material assumes the mechanical load and effectively insulates the conductor with respect to its supporting 25 means.

A switchboard structure is usually provided, at its rear side, with many small control and other circuit conductors which, in certain instances, are so intermingled as to 30 present a disorderly appearance and to render manipulation thereof more or less difficult.

Attempts have been made to arrange these conductors in more orderly and effective 35 fashion, and my invention is particularly adapted for use in connection with an arrangement by which a plurality of conductors are mounted parallel or in other symmetrical relation across the rear of a switchboard.

In practicing my invention, I provide a substantially tubular main body structure of insulating material in which a sleeve is disposed. The sleeve is provided with a longitudinal surface groove to receive the end of 45 a conductor that is bent back into the groove after its insertion through the sleeve and is prevented from withdrawal from the groove and, thereby, from disconnection from the 50 sleeve, by the wall of the tubular member. A screw-threaded member that projects from the opposite end of the tube is secured to, and prevented from turning in, the tube by a transverse pin member that extends

through the tubular member and the screw. 55 The opposite end of the screw is placed through an opening in a bracket or other supporting member and secured by a nut or other holding means by which the tension in the conductor may be adjusted. 60

Figure 1 of the accompanying drawings is a side view, partially in elevation and partially in section, of a connector constructed in accordance with my invention, and Fig. 2 is a view, taken along the line II-II of 65 Fig. 1.

A main insulating body member 1, preferably constructed of fiber or other suitable relatively-hard and strong insulating material, is provided with openings 2 and 3 of 70 different diameters to provide a shoulder 15 therein. A cylindrical sleeve 4, preferably of metal, and of substantially the same diameter as the opening 2, is disposed in the opening 2 adjacent to the shoulder 15, and is provided with a longitudinal groove 5 in its outer surface for the reception of the bared end 6 of an insulated conductor 7 that extends through the opening 3 and the sleeve 4 and is bent back into the groove 5. A 80 screw-threaded member 8 is provided with a head portion 9 disposed in one end of the opening 2 and held therein by a cotter pin 10 that extends through the member 1 and the head portion 9. The opposite end of the 85 member 8 projects through an opening 11 in a bracket 12, or other device for attachment to the rear side of a switchboard, and is adapted to receive a nut 13 and a washer 14 by which the member 1 and, consequently, 90 the conductor 7 may be adjusted longitudinally and held with respect to the bracket 12.

While I have shown and described a particular form of my invention, changes may be effected therein without departing from 95 the spirit and scope thereof, as set forth in the appended claims.

I claim as my invention:

1. A terminal comprising a tubular insulating member having two portions of different interior diameters to provide a shoulder, a sleeve having a longitudinal surface groove and disposed in the larger of said portions against said shoulder, and a conductor extending through the smaller of said portions and said sleeve and having a portion bent back into said groove. 100

2. A terminal comprising a tubular insu-

- lating member having two portions of different interior diameters to provide a shoulder, a sleeve having a longitudinal surface groove disposed in, and closely fitting, the 5 larger of said portions against said shoulder, and an insulated conductor having a portion disposed in the smaller of said portions and an uninsulated portion extending through said sleeve and bent back into said groove.
- 10 3. A terminal comprising a tubular insulating member having a portion of reduced interior diameter at one end to provide a shoulder, a sleeve having a longitudinal surface groove disposed therein against said shoulder, a conductor extending through the smaller end of said insulating member and said sleeve having a portion bent back into said groove and a screw having one end
- secured in the opposite end of said insulating member and projecting therefrom. 20
4. A terminal for a conductor comprising a tubular insulating member having a portion of reduced interior diameter to provide a shoulder, and a sleeve member disposed therein and retained against longitudinal 25 displacement in one direction by the said shoulder, the said sleeve member being provided with a longitudinal surface groove to receive a reversely bent portion of the conductor whereby the conductor is attached to the sleeve. 30

In testimony whereof, I have hereunto subscribed my name this 30th day of March, 1920.

JAMES M. BROWN.
